LADY'S SHOE

Leonard L. Taicher and John S. Tomaselli, Miami, Fla.; said Tomaselli assignor to said Taicher

Filed Apr. 4, 1960, Ser. No. 60,029

Term of patent 14 years

(Cl. D7—5)

FIG. 1 is a side perspective view of a lady's shoe showing our new design. The side opposite thereto being substantially the same in appearance.

FIG. 2 is a bottom plan view thereof.

The dominant feature of the design is the ornamental breasting strip which overlies the forward surface of the heel and the adjacent bottom surface of the sole as shown in full lines in the drawing.

We claim:

The ornamental design for a lady's shoe, as shown and described.
